POWER HAND CHAIN SAW

Gustav H. Sudmeier, 13728 S. Normandy,
Gardena, Calif. 90249

Filed Aug. 10, 1966, Ser. No. 3,414

Term of patent 14 years

(Cl. D93—3)

Fig. 1

Fig. 2

FIG. 3

FIG. 4

FIG. 5

FIGURE 1 is a side plan view of a power hand chain saw, showing my new design;

FIGURE 2 is a top plan view thereof;

FIGURE 3 is a bottom plan view thereof;

FIGURE 4 is a front plan view thereof; and

FIGURE 5 is a rear plan view thereof.

A portion of the drawing is in broken lines; and in this regard the dominant features of the design reside in the full line disclosure.

The ornamental design for a power hand chain saw, substantially as shown and described.
